(57) CLAIM

The ornamental design for a dashboard display mount, as shown and described.

DESCRIPTION

FIG. 1 is a top right front perspective view of a dashboard display mount showing my new design;

FIG. 2 is a front elevational view thereof;

FIG. 3 is a right side elevational view thereof;

FIG. 4 is a left side elevational view thereof;

FIG. 5 is a rear elevational view thereof; and,

FIG. 6 is a top plan view.

The broken line showing of display gauges is for illustrative purposes only and forms no part of the claimed design.
